MULTIPLE FORM ALIGNING DEVICE

Filed May 22, 1936

3 Sheets-Sheet 1

<img alt="A detailed technical line drawing of a mechanical device, likely a lock or safe mechanism, shown in an exploded or partially assembled state. The drawing is labeled with numerous numbers (1, 2, 3, 4, 5, 6, 10, 11, 12, 13, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 339, 340, 341, 342, 343, 344, 345, 346, 347, 348, 349, 349, 350, 351, 352, 353, 354, 355, 356, 357, 358, 359, 360, 361, 362, 363, 364, 365, 366, 367, 368, 369, 369, 370, 371, 372, 373, 374, 375, 376, 377, 378, 379, 379, 380, 381, 382, 383, 384, 385, 386, 387, 388, 389, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2019, 2019, 2020, 2021, 2022, 2023, 2024, 2025, 2026, 2027, 2028, 2029, 2029, 2030, 2031, 2032, 2033, 2034, 2035, 2036, 2037, 2038, 2039, 2039, 2040, 2041, 2042, 2043, 2044, 2045, 2046, 2047, 2048, 2049, 2049, 2050, 2051, 2052, 2053, 2054, 2055, 2056, 2057, 2058, 2059, 2059, 2060, 2061, 2062, 2063, 2064, 2065, 2066, 2067, 2068, 2069, 2069, 2070, 2071, 2072, 2073, 2074, 2075, 2076, 2077, 2078

MULTIPLE FORM ALIGNING DEVICE

Ellsworth J. Nichols, Newark, N. J.

Application May 22, 1936, Serial No. 81,281

9 Claims. (Cl. 197—133)

This invention relates, generally, to means for maintaining multiple forms, such as are used in electric accounting and tabulating machines, in alignment, and the invention has reference, more particularly, to a novel multiple form aligning device adapted to be readily attached to the above mentioned and similar machines for accomplishing this result.

In operating electric accounting and tabulating machines considerable difficulty has been experienced in the past in endeavoring to maintain the several superimposed continuous forms in alignment while passing through the machines due to the slippage between the successive forms. This slippage is cumulative so that with long forms considerable misalignment results between the upper and lower forms and if the forms have printed matter thereon, the typewritten material is not properly located with respect thereto and such typewritten material at times is written upon the printed matter instead of in the spaces therebetween.

The principal object of the present invention is to provide a novel multiple form aligning device that may be readily attached to accounting, tabulating and similar machines and which serves to positively and continuously align the several superimposed continuous length forms both horizontally and vertically, thereby providing for the proper and identical location of the typewritten matter on the original and all of the duplicate form copies.

Another object of the present invention lies in the provision of a novel multiple form aligning device of the above character comprising a frame member carrying pulley driven non-slipping endless belts or tapes having driving pins thereon for engaging in rows of perforations provided in the continuous length forms, to thereby insure the alignment of the forms at all times, the said pulley driven belts operating in synchronism with the machine form feed.

Still another object of the present invention is to provide a novel multiple form aligning device of the above character wherein the aligning belts or tapes are readily adjustable simultaneously to accommodate various widths of continuous length forms and are also simultaneously movable for operating upon forms located at any desired position along the length of the machine platen.

Other objects of this invention, not at this time more particularly enumerated, will be clearly understood from the following detailed description of the same.

The invention is clearly illustrated in the accompanying drawings, in which:

Fig. 1 is a perspective view of the novel multiple form aligning device shown applied to an electric accounting and tabulating machine. 5

Fig. 2 is an enlarged part sectional view of a portion of the structure of Fig. 1.

Fig. 3 is a fragmentary view in plan of a portion of the structure of Fig. 2.

Fig. 4 is a view looking up at the structure of 10 Fig. 3 from below.

Fig. 5 is a perspective view partly broken away of the endless belt aligning means and associated parts.

Fig. 6 is a vertical view taken along line 6—6 15 of Fig. 2.

Fig. 7 is a composite view showing the several parts of the aligning means prior to assembly.

Fig. 8 is a view in elevation of the assembled aligning means of Fig. 7, and 20

Fig. 9 is a perspective view of the structure of Fig. 8 with parts broken away.

Similar characters of reference are employed in said views, to indicate corresponding parts.

Referring now to the several figures of the drawings, the reference numeral 1 designates an electric accounting and tabulating machine of a type well known to those skilled in the art. This machine is adapted to receive a continuous length form 2 supplied from a form pack 3 resting upon the shelf 4 of a stand 5. Form 2 consists of an original and as many form copies as desired, carbon paper being interlined between consecutive superimposed form copies for transmitting the impression of the machine type to 35 all copies simultaneously. The form 2 is provided with a series of equally spaced perforations 6, adjacent its side edges, the said perforations extending through all copies of the form.

The continuous length form 2 passes between 40 metal guides 7 and 8 and then down and around and up and over the cylindrical machine platen 9, whereupon the form passes over the inclined guide 8 and then over the flat guide 10 to be supplied to a receiving pack 11 resting upon a 45 shelf 12 of stand 5.

According to the preferred arrangement, the novel multiple form aligning device of this invention comprises a substantially rectangular frame member 13 that is adapted to extend 50 transversely above the machine 1. The frame member 13 is illustrated as having fixed legs 14 and adjustable legs 15, the legs 15 being adjustably connected to frame member 13 through the use of slots 16 and bolts 17, whereby the

- frame member is made adjustable with respect to machine 1. The frame member 13 is shown in the drawings as inclined somewhat to accommodate the same to the general inclination 5 of the form 2 after it leaves the platen 9. A pair of spaced shafts 18 and 19 extend longitudinally of the frame 13 and have their end portions journaled in the end members of this frame.
10. Shafts 18 and 19 are splined, i. e. provided with key-ways 20 for slidably receiving keys 20' fixed on pulleys 21 and 22 that are slidably though non-rotatably mounted on these shafts. Two sets of pulleys 21 and 22 are employed, the 15 two pulleys 21 being keyed upon shaft 18 and the two pulleys 22 being keyed upon shaft 19. Shaft 18 is suitably connected as by means of a sprocket chain drive 23 and spur gearing 24 to the platen shaft 25, whereby shaft 18 is 20 caused to move in synchronism with the platen shaft 25, this latter shaft serving to drive shaft 18. Looped around the peripheries of pulleys 21 and 22 are endless belts or tapes 26 having regularly spaced outwardly projecting pins 27 thereon, which pins are adapted to engage in the apertures or perforations 6 of the form set, to thereby positively retain all sheets of the form set in alignment while aiding in the movement of the form set.
25. In order to assure that the surface speed of the belts 26 shall be identical with that of the surface of platen 9, the belts 26 are also provided with inwardly projecting pins 28 that are adapted to engage in depressions or pockets 29 provided 30 in the peripheries of pulleys 21 and 22. The gearing 23 and 24 is such that pulleys 21 drive belts 26 at a speed synchronized with the moving form so that any sheets of the form which tend to fall behind the desired speed are prevented from 35 doing so by the pins 27 on belts 26 which pins serve to positively advance these sheets at the same rate as the inner sheet, i. e. the sheet adjacent the platen 9. In order to insure the engagement of pins 27 in perforations 6, suitable 40 guide means are carried by the frame member 13 so as to assure this result.
45. Such guide means comprises a plate member 30 associated with each pair of said pulleys 21—22. This plate member 30 is supported on pulleys 21—22 by being provided with substantially semi-circular recesses 31 in its ends which recesses are adapted to engage around the hubs 36 of pulleys 21—22. The hubs 36 of these pulleys are provided with peripheral annular grooves 50 32 of a width to accommodate the ends of plate member 30 whereby the plate member may be suspended at its ends upon the hubs of pulleys 21—22 as especially shown in Fig. 5, the recesses 31 providing the plate member 30 with forked 55 ends which engage in the grooves 32 and allow the pulleys to turn with respect to the plate member 30. Plate member 30 is provided with a lower guide projection 33 extending at right angles with respect to the main body of plate member 60 30 for overlying the lower run of belt 26 so as to prevent the same from bulging up in use which would cause pins 27 to disengage one or more of the form sheets. This guide projection 33 is provided with a longitudinal slot or aperture 35 65 therein for accommodating the movement of pins 28. Guide 33 is provided with turned up ends 34 and 34' that extend above the pins 28 at the ends of slot 35 to provide metal for supporting the outer part of this guide, the ends 34 and 70 34' also facilitating the passage of the belt there-

under. Plate member 30 is also provided with an additional lower guide projection 37 positioned adjacent pulley 22 for the purpose of guiding the form 2 as it leaves this pulley. The upwardly moving pins 27 on belt 26 as it passes around pulley 22 tend to lift the form 2 upwardly somewhat but such upward lifting is prevented by guide 37. This guide has a recess 38' therein for enabling the passage of pins 27.

75. A bracket 45 is provided with slots 46 for receiving wing bolts 47, whereby this bracket may be adjustably attached to the plate member 30. Bracket 45 is provided with a guide projection 48 of substantially rectangular shape which is adapted to underlie the form set 2 as it passes beneath the belt 26. The end portions of the guide projections 48 are down turned at 49 and 49' to facilitate the passage of the form set 2 thereover. This guide projection is also provided with a longitudinal slot 50 for accommodating the projecting ends of pins 27 that extend below the form set 2. The slots 46 and wing bolts 47 enable the guide projection 48 to be adjusted with respect to guide projection 33 to accommodate form sets of varying thicknesses, the thicknesses of the form sets depending upon the number of sheets therein.

80. In order to accommodate the transverse spacing of belts 26 to various widths of forms the plate members 30 have nuts 51 fixed thereon substantially midway of the length of the same. The nut 51 on one of the plate members 30 is provided with a right hand thread for engaging the right hand threads 52 provided on one half the length of a threaded rod 53. The nut 51 of the other plate member is provided with a left hand thread for engaging the left hand threads 54 on the remaining half of the rod 53. A block 61 is journaled on an unthreaded portion of rod 53 at the mid-length thereof and collars 62 secured to rod 53 at each side of block 61 serve to confine this block to a fixed position longitudinally upon rod 53. Block 61 carries a threaded stud 55 that projects through a slot 56 provided in a bar 57 extending longitudinally of frame member 13 and 85 parallel to rod 53, said bar 57 having its ends fixed upon this frame member. A wing nut 58 threaded upon stud 55 is adapted to bind block 61 to bar 57 thereby holding rod 53 against longitudinal movement. The ends of rod 53 are provided with square heads 59 for receiving a crank 60. By turning rod 53 by means of crank 60 the aligning units, each of which consists of a belt 26, pulleys 21 and 22 and associated parts are moved either towards or from each other thereby 90 accommodating the same to any desired width of continuous form.

95. It will be noted that the hubs 36 of pulleys 21 and 22 are provided with annular grooves 32' similar to grooves 32. Grooves 32' receive the 60 bifurcated or semi-circular recessed ends of plates 38 that are secured to nuts 51 as by screws 39. Plates 38 are provided with circular apertures 40 for accommodating the rod 53. With plate 38 secured to nut 51 and hence to plate member 30, 65 a rigid structure is provided for supporting the guides 33, 37 and 48 upon the hubs of pulleys 21 and 22, and for threadedly connecting rod 53 to the aligning units.

100. In order to accommodate the aligning units to forms placed at different positions along the length of the platen 9, it is merely necessary to loosen wing nut 58 and move rod 53 longitudinally, thereby simultaneously moving the aligning units consisting of belts 26, pulleys 21 and 22. 75

plate members 30 and brackets 45 to the position desired transversely of the machine 1. After locating the spaced aligning units in the position desired, the nut 58 is again tightened. The ends 5 of frame members 13 are provided with apertures to accommodate longitudinal movements of the rod 53 therethrough.

In use, the platen shaft 25 acts through gearing 24, 23 to drive shaft 18 which in turn drives 10 pulleys 21 of the aligning units, which pulleys in turn drive belts 26 so that the surface speed of these belts is the same as that of platen 9. Pins 28 on belts 26 by engaging in pulley recesses 29 prevent these belts from slipping so that the pins 15 27 of belts 26 engaging in the form apertures 6 serve to advance the form 2 at a rate truly synchronous with that imparted to the form 2 by platen 9. Guides 33 and 48 serve to insure the proper engagement of pins 27 in apertures or 20 perforations 6 of the form 2 and prevent the transverse distortion of this form while passing the aligning units; the guides 48 serving to support the form, and the guides 33 serving to hold the lower rim of belt 26 down in proper engagement 25 with the form so that pins 27 shall engage all sheets thereof to cause all such sheets to advance with the same intermittent motion and at the same rate of speed.

When it is desired to change from one width of 30 form to another it is merely necessary to turn crank 60, thereby accomplishing this result. The adjustment of rod 53 longitudinally of bar 51 by means of wing nut 58 serves to place the form in any transverse position desired across the machine.

As many changes could be made in the above construction and many apparently widely different embodiments of this invention could be made without departing from the scope thereof, as 40 defined by the following claims, it is intended that all matter contained in the above description or shown in the accompanying drawings shall be interpreted as illustrative and not in a limiting sense.

I claim:—

1. In a multiple continuous form aligning device for retaining the form copies of a form set in alignment while passing through a machine, an aligning unit comprising, an endless belt, spaced pulleys for supporting said endless belt driven by one of said pulleys, projecting pins provided on said belt for engaging in perforations in the form set, guides carried by said pulleys for holding the form set in engagement with the pins of a run of said belts, said guides being longitudinally slotted to accommodate movement of said pins, and means for rotating said driving pulley whereby said belt moves synchronously with the machine drive of said form set.

2. In a multiple continuous form aligning device for retaining the form copies of a form set in alignment while passing through a machine, an aligning unit comprising, spaced pulleys for supporting an endless belt driven by one of said pulleys, said belt having a run thereof adjoining and extending parallel to said form set, projecting pins provided on said belt for engaging in perforations in the form set, guide members carried by said pulleys for confining said form set and said belt run therebetween while said form set is in engagement with the pins of said belt, to thereby insure the projection of said pins through all sheets of said form set, and gearing operated from the machine for rotating said driving pulley so that said belt moves at the

same speed as the machine drive of said form set.

3. In a multiple continuous form aligning device for retaining the form copies of a form set in alignment while passing through a machine, 5 an aligning unit comprising, spaced pulleys for supporting an endless belt driven by one of said pulleys, said belt having a run thereof adjoining and extending parallel to said form set, cooperating pin and socket means on said belt and driving pulley for eliminating slippage of said belt, projecting pins provided on said belt for engaging in perforations in the form set, guide members carried by said pulleys for confining said belt run and said form set therebetween, 15 whereby all form copies of the form set are engaged by said projecting pins, and means for rotating said driving pulley whereby the surface speed of said belt is the same as the machine speed of said form set. 20

4. In a multiple form aligning device for accounting, tabulating and similar machines, a frame member mounted on the machine in overlying relation to a form set moving from the platen of the machine, aligning units carried by 25 said frame member, said aligning units comprising endless belts provided with projecting pins for engaging perforations in the marginal edges of said form set, and screw means provided on said frame member for moving said aligning units 30 simultaneously for accommodating varying widths of form sets.

5. In a multiple form aligning device for accounting, tabulating and similar machines, a frame member mounted on the machine in overlying relation to a form set moving from the platen of the machine, aligning units carried by 35 said frame member, said aligning units comprising endless belts provided with projecting pins for engaging perforations in the marginal edges 40 of said form set, screw means provided on said frame member for moving said aligning units simultaneously toward and away from each other for accommodating varying widths of form sets, and additional means for moving said aligning 45 units simultaneously across the machine to accommodate form sets at various positions along the machine platen.

6. In a multiple continuous form aligning device for accounting, tabulating and similar machines, a substantially rectangular frame member having legs for mounting the same on the machine, parallel spaced shafts journaled in the ends of said frame member, a form aligning unit comprising pulleys mounted for longitudinal sliding movement on said shafts, an endless belt mounted on said pulleys and having projecting pins for engaging perforations in the form set after the same leaves the machine platen, guide members carried by said pulleys and serving to hold a run of said belt in cooperative engagement with said form set, and power transmission means connecting the platen shaft to one of said parallel shafts for driving a pulley of said aligning unit, whereby said belt moves synchronously 55 with the machine platen. 60

7. In a multiple form aligning device for accounting, tabulating and similar machines, a substantially rectangular frame member having legs for mounting the same on the machine, parallel 70 spaced shafts journaled in the ends of said frame member, a form aligning unit comprising pulleys mounted for longitudinal sliding movement on said shafts, an endless belt mounted on said pulleys and having projecting pins for engaging per-

forations in the form set after the same leaves the machine platen, guide members carried by said pulleys and serving to hold a run of said belt in cooperative engagement with said form set, and power transmission means connecting the platen shaft to one of said parallel shafts for driving a pulley of said aligning unit, whereby said belt moves synchronously with the machine platen, and screw means for setting said form 10 aligning unit at selected points along the length of said frame member.

8. In combination, an accounting and tabulating machine having a cylindrical platen for driving a continuous form set and an aligning 15 device for maintaining the several copies of the form set in alignment, said aligning device comprising, a frame member mounted on said machine above the form set, a pair of spaced parallel shafts carried by said frame member, means for 20 driving one of said shafts from said platen, a pair of aligning units carried by said shafts, each of said aligning units comprising pulleys mounted on said shafts, a belt passing over said pulleys and having projecting pins for engaging perfora- 25 tions in the form set, and guides carried by said

pulleys for holding said belt in cooperative engagement with the form set.

9. In combination, an accounting and tabulating machine having a cylindrical platen for driving a continuous form set and an aligning device 5 for maintaining the several copies of the form set in alignment, said aligning device comprising, a substantially rectangular frame member mounted on said machine above the form set, a pair of spaced parallel shafts carried by said frame member, 10 means for driving one of said shafts from said platen, a pair of aligning units carried by said shafts, right and left hand screw means for moving said aligning units toward and from each other along said shafts, and means for moving 15 said aligning units together along said shafts and transversely of said machine, each of said aligning units comprising pulleys mounted on said shafts, a belt passing over said pulleys and having projecting pins for engaging perforations in 20 the form set, and guides carried by said pulleys for holding said belt in cooperative engagement with the form set.

ELLSWORTH J. NICHOLS. 25
